UNITED STATES PATENT OFFICE.

ALBERT A. PAGE, OF EAST HAVEN, CONNECTICUT, ASSIGNOR TO SARGENT & COMPANY, OF NEW HAVEN, CONNECTICUT, A CORPORATION OF CONNECTICUT.

LOCK.

1,316,178.

Specification of Letters Patent. Patented Sept. 16, 1919.

Application filed May 3, 1916. Serial No. 95,230.

To all whom it may concern:

Be it known that I, ALBERT A. PAGE, a citizen of the United States, residing in East Haven, county of New Haven, and 5 State of Connecticut, have invented certain new and useful Improvements in Locks, of which the following is a full, clear, and exact description.

This invention relates to locks, and more 10 particularly to means for securing a mortise lock within a hollow metal door stile.

One of the primary objects of the invention is to furnish a lock construction in which a pair of escutcheons coöperate with 15 suitable fastening members at the top and bottom of the mortise lock case in such a manner as to secure the lock firmly in the hollow metal stile without the necessity of screwing or otherwise directly connecting 20 the face plate or front of the lock to the stile.

The invention also has in view the general improvement in construction and application of devices of the class to which 25 the invention relates.

To these and other ends, the invention consists in the novel features and combinations of parts to be hereinafter described and claimed.

30 In the accompanying drawing,

Figure 1 is a fragmentary outside view of a metal door equipped with my improvements;

Fig. 2 is an edge view of the door;

35 Fig. 3 is a section on line 3—3 of Fig. 1;

Fig. 4 is a section on line 4—4 of Fig. 1;

Fig. 5 is a side elevation of the mortise lock; and

40 Figs. 6 and 7 are fragmentary details of the outside escutcheon.

In the drawing, the hollow metal door stile 10 is shown as constituted by a metal tube of generally rectangular cross-section as usual. At the edge of the door, the stile

45 is provided with an elongated slot 11 to receive the face plate or front 12 of a mortise lock 13 housed within the stile. The slot 11 extends completely through the wall of the metal tube and corresponds in contour

50 with the face plate 12, which fits snugly in said slot with its outer face substantially flush with the outer face of the metal tube.

In the particular form shown, the mortise lock 13 is provided with a latch bolt 14 adapted to be retracted by inside and out-

side lever handles or other manual retracting devices 15, 16 respectively, and also by a key fitting a cylinder lock 17. The cylinder lock 17 and the outer lever handle 16 pass through an outside escutcheon 18, and 60 the inside lever handle 15 passes through an inside escutcheon 19.

At the upper part of the case of the mortise lock are a pair of upwardly projecting lugs 20, which are preferably cast on the 65 main body portion of the lock case and independent of the usual cap plate. Preferably these lugs 20 are of the same thickness as the lock case, one face of each lug being flush with the cap plate, and the opposite 70 face of said lug being flush with the back of the lock. A bore or perforation 21 extends through each lug. Similar lugs 20 are also provided at the lower part of the case, as shown in Fig. 5. The outside escutcheon 75 18 is provided with inwardly projecting sleeve members or sockets 22 near the respective corners of said escutcheon, said sleeve members or sockets 22 being provided with interior screw threads 23 80 (Fig. 7), and the inside escutcheon 19 is provided near the corners thereof with sleeve-like members or sockets 24 adapted to aline with the sockets 22 and with the lugs 20 of the mortise lock case. The sockets 85 or sleeves 24 on the inside escutcheon are provided with smooth bores or perforations, which extend entirely through said escutcheon and the perforations of both escutcheons are adapted to engage suitable holes or 90 perforations in the corresponding wall of the stile, as shown in Fig. 4. A fastening screw 25 passes through each sleeve 24, and through each perforated lug 20 into the alined threaded sleeve 22 of the outside 95 escutcheon, and said screw is provided with threads at its inner end to engage those of the socket or sleeve 22, whereby the parts may be clamped in the assembled position. It will be understood, therefore, that the 100 escutcheons are supported flatwise against the inner and outer walls of the hollow door stile with their sleeves projecting into the hollow interior of the stile to a certain extent. When the parts are in the assembled 105 position, these sleeves extend into substantial contact with the adjacent faces of the lugs 20, and by making all of the sleeves of the same length, the mortise lock may be firmly and securely clamped in place 110

centrally of the door stile with the face plate in its proper position in the slot 11. By fastening the mortise lock to the four corners of the escutcheons in the manner described, the lock is very securely held against displacement, and it will be apparent that the lock can be very readily and conveniently mounted. In mounting the lock, the same is inserted into the door stile 10 through the slot 11, so that the face plate takes its proper position in the stile 11. At this time, the openings 21 of the several lugs 20 will register with the openings which have been drilled in the inner and 15 outer walls of the stile for the sleeves or sockets 22, 24. When the lock 13 is inserted into the stile, it is preferably arrested in the proper position by stop members or lugs 26 projecting rearwardly from the body 20 portion of the case into contact with the rear wall 27 of the hollow stile member, as shown more particularly in Figs. 3 and 4. When the lock has been properly positioned, the escutcheons can be very readily applied 25 in an obvious manner, and the cylinder lock is then mounted in the usual way.

I do not claim broadly herein the combination of a metal hollow stile having a slot at the edge of the door, a mortise lock 30 in said stile having a face plate located in said slot, said face plate carried by the mortise lock but separate from the stile, escutcheon members applied to the inside and outside walls of the stile, and a transverse 35 fastening member interconnecting said escutcheon members and passing through a part of said mortise lock for securing it in place, as claimed in my application, Serial No. 95,229, filed on even date herewith.

40 Without limiting myself to the precise construction shown, I claim:

1. In a lock for metal doors, the combination of a hollow metal stile, a mortise lock case therein having its side walls spaced 45 from the opposing side walls of the stile, escutcheons applied to the respective side walls of the stile, lugs upon said escutcheons for holding the side walls of the lock spaced from the walls of the stile, and fastening 50 members interconnecting said escutcheons and passing through the top and bottom respectively of the case for securing it in place in said stile.

2. In a lock for metal doors, the combination of a hollow metal stile of substantially 55 rectangular cross-section having an elongated slot in that wall located at the edge of the door, a mortise lock in said stile having a face plate located in said slot, the side 60 walls of the stile having registering perforations located at the top and bottom of the lock case, and the side faces of the lock case being spaced from the side walls of the stile, escutcheons applied to the side walls of the 65 stile and having sleeves adjacent to the cor-

ners thereof extending through said perforations into contact with the side faces of the lock case, and fastening screws at the top and bottom of each escutcheon passing through said sleeves for clamping the lock 70 case in the stile.

3. In a lock for metal doors, the combination of a hollow metal stile having a slot at the edge of the door, a mortise lock in said stile having a face plate located in said 75 slot, said face plate carried by said mortise lock but separate from said stile, lugs formed upon said lock projecting therefrom, escutcheons applied to the outside and inside faces of said stile, and transverse fastening 80 members interconnecting said escutcheons at the corners thereof and passing through said lugs to secure said lock in the stile; substantially as described.

4. In a lock for metal doors, the combination of a hollow metal stile having a slot at the edge of the door, a mortise lock in said stile having a face plate located in said slot, said face plate carried by the mortise lock but separate from the stile, escutcheons applied to the outside and inside faces of said 90 stile and having sleeves engaging openings in the stile walls at the corners of said escutcheons, and transverse fastening members interconnecting said sleeves and clamping the lock therebetween; substantially as 95 described.

5. The combination of a hollow stile member, a lock fitted therein and having a plurality of perforated lugs at the upper part 100 thereof and a plurality of perforated lugs at the lower part thereof, escutcheon members each having sleeves engaging openings in the wall of the hollow stile member and alined with said lugs, and fastening screws 105 interconnecting the sleeves and passing through said lugs; substantially as described.

6. The combination of a hollow stile member having a slot at the edge of the door, 110 a lock housed within said stile member, and having a face plate lying in said slot, two lugs projecting upwardly from said lock at at the upper part thereof, two lugs projecting downwardly from said lock at the lower 115 part thereof, a pair of escutcheons, and fastening members passing through the inner escutcheon and said lugs and having threaded engagement with the outer escutcheon; substantially as described.

7. In a lock for metal doors, the combination of a hollow metal stile, a lock fitted 120 therein, one wall of said stile having perforations, a plate applied to the outside surface of said wall and having members engaging said perforations, and means including clamping bolts engaging said socket members and extending through said lock for securing said plate against the outer surface of said wall with said lock in rigid 130

engagement with the ends of said socket members, substantially as described.

8. In a lock for metal doors, the combination of a hollow metal stile having a slot in one wall, a lock fitted within said stile and having a face plate in said slot, plates applied to the outside and inside faces respectively of said stile, and fastening members interconnecting said plates and supporting the lock in place in the stile; substantially as described.

9. In a lock for metal doors, the combination of a mortise lock case having a plurality of perforated lugs, escutcheons having a plurality of inwardly extending sockets to align with said lugs, and fastening screws to engage the sockets and lugs and thereby clamp said mortise lock case in position between said plates; substantially as described.

10. In a lock for metal doors, the combination of a hollow metal stile having a slot in one wall, a mortise lock in said stile having a face plate located in said slot, escutcheon members at the outside and inside of the door, means for preventing movement of said escutcheon members in a plane parallel to the door, means contacting with the side

walls of the lock to space the same from the side walls of the stile, and screws for supporting said lock from and between said escutcheon members; substantially as described.

11. In a lock for metal doors, the combination of a hollow metal stile, a mortise lock fitted therein, an escutcheon for said lock, projections formed upon said escutcheon extending through the side wall of the stile and into abutting engagement with a lateral face of said lock, and common means for securing the escutcheon and lock in place.

12. In a lock for metal doors, the combination of a hollow metal stile, a lock mounted therein, said lock having a plurality of lugs projecting from the opposite ends thereof, means passing through the side walls of the stile and through said lugs for securing said lock within the stile, and additional means extending inwardly from said side walls engaging said lugs and spacing the same from said side walls.

In witness whereof, I have hereunto set my hand on the 1st day of May, 1916.

ALBERT A. PAGE.
